UNITED STATES PATENT OFFICE.

CHARLES D. GOLDEN, OF CHICAGO, ILLINOIS.

DESIGN FOR A CLOCK-CASE.

SPECIFICATION forming part of Design No. 26,557, dated January 26, 1897.

Application filed December 18, 1896. Serial No. 616,195. Term of patent 31 years.

To all whom it may concern:

Be it known that I, CHARLES D. GOLDEN, of Chicago, in the county of Cook and State of Illinois, have invented and produced a new and original Design for Clock-Cases, of which the following is a specification, reference being had to the accompanying drawing, in which the figure is a front elevation of a clock-case, illustrating my design.

10 The leading feature of my design consists of the representation in bas-relief of a castle or castelated structure, in the central portion of the elevation of which, beneath an archway, is located a clock-face.

15 Referring to the drawing, *a* represents the base of the structure, formed to represent masonry. Said base is wider than the superimposed structure and is represented as extending rearwardly in oblique lines. Flanking the corners of the structure are conventional forms *b c*, representing plants and trees, respectively, while a semicircular archway *d* is shown in the middle having a barred opening beneath.

25 The main feature of the façade consists of

a rectangular frame *e*, having a circular archway above the clock-face and open scroll-work *f* beneath. A gable *g*, having windows therein, surmounts the façade, upon the apex of which is located a flag-pole and flag. The 30 façade is flanked upon the left by a buttress and oriole window *h*, bearing a flag-pole and streamer at the top, and upon the right by a wing showing two similar windows *i j*, a cornice *k*, a round window *l* above, from which is protruded a flag-pole and flag, while above the latter window is a receding gable *m*, showing a chimney and dormer-window. A battlement *n* is shown between the oriole window *h* and the main gable *g*.

40

I claim—

The design for a clock-case, substantially as shown and described.

In testimony whereof I have signed this specification, in the presence of two subscribing witnesses, this 7th day of December, 1896.
